Attorney

UNITED STATES PATENT OFFICE

GEORGE F. WILDE, OF KEYPORT, NEW JERSEY

FILTER

Application filed September 4, 1929. Serial No. 390,303.

This invention relates to filters and more particularly to devices of this character of the type wherein the filtering is accomplished by means of centrifugal force, propelling or 5 driving the fluid portions of the slip or material to be filtered through a suitable filtering material, the solid portion of said slip being retained by said filtering material.

One object of the invention is to provide 10 in a manner as hereinafter set forth a filter of the aforementioned character, having means for progressively feeding the material from which the fluid has been extracted to a point of discharge.

15 Another object of the invention is to provide, in a manner as hereinafter set forth, a device of the aforementioned character, wherein the movement of the material from which the fluid content has been extracted 20 toward the point of discharge is accomplished by means of the rotary movement of the filtering element.

Other objects of the invention are to provide 25 a device of the character set forth which will be simple in construction, strong, durable, efficient in its use and which may be manufactured at low cost.

Other objects and advantages of the invention will be apparent from a study of the following specification, taken in connection with 30 the accompanying drawings, wherein like characters of reference designate corresponding parts throughout the several views, and wherein:

35 The figure illustrating the invention is a view in partial vertical section, illustrating a filtering device constructed in accordance with this invention.

Referring to the drawings in detail, the 40 reference character 1 designates generally a rotatable cylinder having a perforated cylindrical body portion or side walls 2, and oppositely extending conical end walls 3 and 4. The lower end of the conical end wall 4 45 terminates in a sleeve 5 of uniform diameter, which rests upon the upper face of a suitable support or bracket 6 for the purpose of supporting the cylinder 1. The apex of the upper conical end wall 3 is provided 50 with a trunnion or pivot pin 7, which

projects upwardly to a supporting bracket 8 and has mounted on its upper or free end, a drive pulley 9, upon which a drive belt 10 is mounted for transmitting power to the cylinder 1 from a suitable source. A filtering agent or material 11 is applied to the inner periphery of the perforated wall 2 of the cylinder and is held in place thereagainst by a filter cloth 12. Extending longitudinally through the cylinder 1 is a substantially cylindrical core member or conveyor screw which is designated generally by the reference character 13. The conveyor screw 13 is provided on the periphery with a spiral rib 14, which extends over the entire length of the cylindrical portion of the conveyor. The opposite ends of the conveyor screw 14 are provided with conical portions 15 and 16. The lower conical portion 16 is provided with a downwardly extending shank 17 which passes through the sleeve 5 and the supporting bracket 6, to which said shanks may be secured as by a key for the purpose of holding the screws 13 against rotation. A conveyor pipe 18 has one end supported in the bracket 6 and communicates with a passage-way 19 formed in the shank 17, which opens into the container or cylinder 1, as clearly illustrated in the drawings.

It will be apparent that the shank 17 functions as a means for retaining the sleeve 5 against lateral movement upon the bracket 6. Near its apex, the upper end wall 3 of the cylinder 1 is provided with an internally disposed web portion 20 which is provided with a centrally disposed opening for the reception of a trunnion 21 mounted on the conical portion 15, of the cylinder 13. A discharge spout or pipe 22 is also mounted in the upper conical end wall 3. As clearly illustrated in the drawings, the outer face of the spiral rib 14 is spaced inwardly from the filtering cloth 12.

In use, the slip or the material to be filtered is pumped from the tank, not shown, through the pipe 18 and passes into the cylinder 1, through the passage 19 formed in the shank 17. It is to be understood, of course, that the cylinder 1 is being rapidly rotated, through

the medium of the pulley 9 and belt 10. The rotary movement of the cylinder 1 causes the fluid contents of the slip to be thrown outwardly by centrifugal force through the filter cloth 12 and the filtering material 11 and then through the perforated side walls 2 of the cylinder, in a well known manner.

The solid material which is retained in the container by means of the filtering elements 11 and 12, is carried around with the cylinder 1, which rotary movement causes said solid material to be fed upwardly and out through the discharge spout 22, by means of the relatively stationary spiral rib 14 on the conveyor screw 13.

It is thought that the many advantages of a filter constructed in accordance with this invention will be readily understood, and although the preferred embodiment of the invention is as illustrated and described, it is to be understood that changes in the details of construction may be had, which may fall within the scope of the invention as claimed.

What is claimed is:

A filter of the character described comprising a rotary cylindrical container having side walls adapted for the passage of the extracted material, said container further including conical end walls, upper and lower supporting brackets, a trunnion formed integrally on the apex portion of one of the end walls extending rotatably through the upper bracket, a drive pulley fixed on the upper end portion of the trunnion above the upper bracket, a tubular sleeve formed integrally on the apex portion of the opposite end wall and disposed rotatably in abutting engagement with the upper side of the lower bracket, a supply pipe extending into the lower bracket, a perforated bearing plate formed integrally in the upper end wall in spaced relation to the apex thereof, a stationary screw conveyor extending longitudinally through the container in spaced concentric relation thereto, said conveyor having substantially conical opposite end portions extending into the conical end walls of the conveyor, an integral trunnion on one end of the screw conveyor mounted for rotation through the bearing plate, an integral shank formed on the opposite end portion of the screw conveyor and extending downwardly through the sleeve and the lower supporting bracket, the sleeve adapted for rotation on the shank and the shank fixed to the lower bracket in a manner to retain the screw conveyor against rotation, said shank constituting means for retaining the sleeve against lateral movement on the lower bracket, said shank further having a fluid passage extending therethrough communicating, at one end, with the interior of the container and at its opposite end with the

supply pipe, and a discharge conduit communicating with the container adjacent its upper end.

In testimony whereof I affix my signature.

GEORGE F. WILDE.
